(57) **CLAIM**

The ornamental design for a disinfectant sheet for toilet, as shown and described.

DESCRIPTION

FIG. 1 is a front view of a disinfectant sheet for toilet showing my new design;

FIG. 2 is a rear view thereof;

FIG. 3 is a right side view thereof which is identical to the left side view;

FIG. 4 is a top plan view thereof, which is identical to the bottom view;

FIG. 5 is a partially enlarged front view showing a portion defined by lines 5-5 in FIG. 1;

FIG. 6 is a partially enlarged front reference view showing the portion defined by lines 5-5 in FIG. 1;

FIG. 7 is a sectional end view of a portion defined by lines 7-7 in FIG. 6;

FIG. 8 is a sectional end view of a portion defined by lines 8-8 in FIG. 6; and,

FIG. 9 is a sectional end view of a portion defined by lines 9-9 in FIG. 6.

The article pertaining to the design of the subject application is a sheet to be used for cleaning a toilet or the like. The sheet of this article is impregnated with an alcohol.
